Chamberlain & Neuman ATTORNEYS.

UNITED STATES PATENT OFFICE.

FREDERICK A. CALKINS, OF WATERBURY, CONNECTICUT.

CHAIN-LINK OPENING AND CLOSING DEVICE.

Application filed April 17, 1922. Serial No. 552,576.

To all whom it may concern:

Be it known that FREDERICK A. CALKINS, a citizen of the United States, and resident of Waterbury, in the county of Fairfield 5 and State of Connecticut, has invented certain new and useful Improvements in Chain-Link Opening and Closing Devices, of which the following is a specification.

My invention relates to new and useful 10 improvements in chain-link opening and closing devices, such as are adapted for opening and closing the eye portions of wire chain-links.

The object of the invention is to provide a 15 simple and inexpensive form of tool, whereby the eyes of wire links such as are commonly employed for the attachment of cross chains, in non-skid chains, so as to simplify the task and lessen the time required in re- 20 placing broken cross-chains of the above class. Further to provide a device of the kind specified which will be equally well adapted for opening and closing other forms of wire links as may be necessary for the 25 lengthening and shortening of wire chains or for the connection of two or more chains together.

With these and other objects in view the 30 invention resides and consists in the construction and novel combination and arrangement of parts hereinafter more fully described, illustrated in the accompanying drawings, and pointed out in the claim here- 35 to appended, it being understood that various changes in the form, proportion, size and minor details of construction within the scope of the claim may be resorted to without departure from the spirit or sacrificing any of the advantages of the invention.

Similar characters of reference denote like 40 or corresponding parts throughout the several figures of the accompanying drawings forming a part of this specification, and upon which,

Fig. 1 shows a front perspective view of 45 my improved chain-link opening and closing device having a wire chain-link positioned therein;

Fig. 2 is a side elevation of the device 50 shown in Fig. 1 including a chain-link and showing a removable handle for operating the cam;

Fig. 3 shows a perspective view of the 55 front portion only of the device shown in

Fig. 1, the chain-link being in position to be 55 operated on to open its eyes rather than closing them as suggested by Fig. 1, and

Fig. 4 shows a detached perspective view of a wire link such as is commonly employed 60 as an end link in cross chains for the attachment of the same to the side chains, of a non-skid chain of the Weed type.

As will be noted from the drawing, my 65 device is comparatively simple in construction and is designed as a portable tool, adapted to be positioned upon a work table or bench for hand-operations. It is further constructed so as to have more power and a larger range of usefulness than that obtained 70 by the ordinary simple form of pincher or tongs as are now commonly employed for opening and closing cross-chain links.

Referring in detail to the characters of 75 reference marked upon the drawings, 5 represents an elongated bed plate which in practice is designed to form the base of the tool, to be seated or positioned upon a work bench when in operation. The top side of the forward end portion of this plate is provided 80 with two longitudinal recesses *a* and *b* arranged side by side and at proper distances apart to receive the eye portion of a wire-link and to support the link longitudinally upon the bed plate as shown in Figs. 1 and 2. This portion of the base plate is also 85 provided with a cross groove *c* forming pockets to accommodate the lower edge portion of the two teeth 6 of the jaw 7.

The jaw 7 is hinged at 8 to a post 9 secured to the bed plate 5 and is arranged 90 longitudinally and upon the bed plate, the two said teeth 6 and 7 being disposed downwardly from its forward end portion in alignment with the before mentioned recesses *a* and *b* in the top side of the base 95 plate. The teeth are in alignment with each other but are spaced apart forming a rounded shouldered portion 10 on the under face of the forward end of the said jaw which as will be seen from Figs. 1 and 2 100 serve to engage the free end portions of the wire link in a way to bend the same down against the loop portion of said link the teeth adapted to prevent outward bending of the link during such closing action. 105 The jaw 7 is normally held in its raised or open position by means of a spring 11, positioned between it and the base plate, the

end portions of said springs being engaged by aligned lugs 12-12 one upon the base and the other upon the jaw.

The jaw is further supported and guided by two vertically disposed bearing posts 13-13 which may be secured to or formed integral with the base plate and disposed up from each side thereof and in alignment with each other, so that their upper end portions which form the bearings extend above the jaw and in position to receive the shaft 14 upon which a cam 15 is rockably mounted. This cam may be provided with a hole 16 as shown to receive a detachable operating handle 17 whereby the cam is rotated in one direction to close the jaw against the action of the spring, and turned in the reverse direction to release the jaw and permit the spring to open the same to its normal position as shown in Figs. 1, 2 and 3.

A link of the class shown in the drawings may be closed by positioning it in the device as shown in Figs. 1 and 2, the body portion of the link resting in the grooves of the base plate and the free end portions of the eye disposed forward in position to be engaged by the shoulder portion 10 of the jaw which serves to engage the said wire ends and force them down to close the eye of the link by the operation of cam 15. I have preferably shown the chain-link positioned in the device, unattached to a chain though it will be obvious of course that most link closing operations of this sort would be required only after the link had been connected to join two pieces of chain together. This closing operation can thus obviously be accomplished with the links attached, or not, as desired.

The teeth portions of the jaw are utilized in the opening of the links as suggested by Fig. 3 in which case the link is disposed crosswise and its eye portion positioned immediately beneath either of the said teeth so that the wedge shaped end portion of the same will enter the eye in a way to spread and open the same from the body portion of

the wire link for the purpose of opening the said eye. In performing this operation the 50 link can be positioned in the device as shown in Fig. 3, or the loop portion may be disposed in an opposite direction in which case the opposite tooth *a* would operate upon the eye of the link instead of the tooth *b*. The 55 operation, however, in both instances is the same and is very simple and effective.

Having thus described my invention, what I claim and desire to secure by Letters Patent is,

In a wire chain link opening and closing device of the character described, the combination with a base member adapted to support a wire link of the character having parallel side portions and end portions 65 looped upon the side portions in parallel vertical planes, said base having parallel grooves adapted to receive the parallel side portions of the links, and aligned grooves at right angles to and extending outwardly 70 from said parallel grooves, a jaw, one end of which is hingedly attached to said base and the other end of which comprises a pair of spaced projections extending toward the base in substantially adjacent relation 75 to the outer edges of said parallel grooves, their edges adapted upon closing of the jaws to engage said aligned grooves, the inner sides of said projections being parallel with each other, and a loop bending portion disposed between said projections, its loop engaging surface being at right angles to the inner parallel surfaces of said projections and in spaced relation to the lower ends thereof, and means for moving the jaw toward the base under pressure whereby the loops of the link are closed by said loop bending portion and are prevented from outward movement by said projections.

Signed at Waterbury in the county of 90 New Haven and State of Connecticut this 12th day of April, A. D. 1922.

FREDERICK A. CALKINS.
